CLAIM

The ornamental design for a portable electric circular saw body, as shown and described.

DESCRIPTION

FIG. 1 is a front perspective view of a portable electric circular saw body in accordance with our new design; FIG. 2 is a rear perspective view of the portable electric circular saw body in accordance with our new design; FIG. 3 is a front elevational view of the portable electric circular saw body in accordance with our new design; FIG. 4 is a rear elevational view of the portable electric circular saw body in accordance with our new design; FIG. 5 is a top plan view of the portable electric circular saw body in accordance with our new design; FIG. 6 is a bottom plan view of the portable electric circular saw body in accordance with our new design; FIG. 7 is a right side elevational view of the portable electric circular saw body in accordance with our new design; FIG. 8 is a left side elevational view of the portable electric circular saw body in accordance with our new design; and, FIG. 9 is a rear perspective view, similar to FIG. 2, of the portable electric circular saw body in accordance with our new design illustrating a state in which a battery is attached to the portable electric circular saw body.

The broken line showing of the battery in FIG. 9 is provided for the purpose of illustrating environmental structures; whereas the broken line showing in FIGS. 2 and 4-6 and the broken line showing in FIG. 9 other than the battery illustrate portions of the portable electric circular saw body. These broken line subject matters do not form part of the claimed design.

1 Claim, 9 Drawing Sheets
